UNITED STATES PATENT OFFICE.

GEORGE HENRY SIBLEY, OF SPRINGFIELD, MASSACHUSETTS.

ROLL-TOILET-PAPER MACHINE.

No. 886,832.

Specification of Letters Patent.

Patented April 28, 1908.

Application filed June 8, 1905. Serial No. 264,257.

To all whom it may concern:

Be it known that I, GEORGE HENRY SIBLEY, a citizen of the United States of America, residing at Springfield, in the county of 5 Hampden and Commonwealth of Massachusetts, have invented a new and useful Roll-Toilet-Paper Machine, of which the following is a specification.

My invention relates to improvements in 10 machines for perforating, slitting and rolling paper, particularly that to be used for toilet purposes, and consists essentially of mechanism for advantageously handling the paper from the large roll, as received from the mill, 15 while being perforated and slit and until it is finally formed into small rolls ready for the market, such mechanism comprises perforating, slitting and rolling means, together with subsidiary or auxiliary parts or members 20 more or less closely allied therewith, all as hereinafter set forth.

The principal objects of my invention are, first, to provide a durable, compact and simple machine for the purpose above designated, 25 whereby the output of toilet paper may be increased in an economical manner, owing to the high rate of speed at which my machine can be run without tearing or otherwise injuring the paper; second, to actuate the paper 30 evenly through the machine without twisting and wrinkling it; third, to furnish a suitable tension or retarding device for the large or original paper supply roll; fourth, to furnish a suitable driving tension device for the small 35 rolls or their winding spindle; fifth, to provide suitable mechanism for perforating the paper without tearing it; sixth, to provide mechanism for slitting the paper (and trimming when necessary) also without tearing it, and, 40 seventh, to furnish a winding spindle which not only tightly holds the paper wound thereon, but is so constructed that it can be easily and quickly withdrawn from the finished or full rolls.

My machine can be driven by a single belt and is otherwise so constructed as to be conveniently controlled at all times, in fact, some parts are automatically governed, all with a view to speed without undue loss of 50 time, or of paper consequent upon tearing the same or spoiling it in some other manner for the purpose for which it is intended. With this machine a saving in time, labor and material is effected.

I attain the objects and secure the advantages above pointed out, by the mechanism

illustrated in the accompanying drawings, in which—

Figure 1 is a longitudinal section on lines $x-x$, Fig. 3, of my machine; Fig. 2, a detail view showing the gears on the ends of the perforating rollers; Fig. 3, a plan view of the machine; Fig. 4, an enlarged sectional view of one of the driving tension devices for the winding spindle; Fig. 5, an enlarged sectional view of one end of the winding spindle, showing the method of connecting the same with its driving shaft; Fig. 6, an enlarged cross-section of said spindle, on lines $y-y$, Fig. 7, looking toward the right; Fig. 7, an enlarged 65 side elevation of the spindle, the middle portion being broken out; Fig. 8, an enlarged cross-section through the perforating rollers, one of the slitters also being shown; Fig. 9, an enlarged side elevation of the combined 70 perforating and slitting roller, and, Fig. 10, a side elevation of the tension or retarding device which may be employed with the paper supply roll shaft.

Similar letters and figures refer to similar 80 parts throughout the several views, and the arrows indicate the directions of moving parts.

Although the accompanying drawings and the description thereof, which I am about to 85 give, show and explain a practicable and efficient embodiment of my invention in a machine, it is to be understood that changes of minor importance, such as alterations in shape and size, the omission of some one or 90 more parts, and changes in construction, which fall within the scope of my claims, may be made without departing from the nature of my invention.

Passing now to the consideration of the 95 machine as illustrated I will proceed to describe the same in detail, both as to construction and operation. A frame is first provided, consisting of two side-pieces a connected by a cross-piece b and rods c . At one 100 side of the front end of the frame is an upright or standard d . The frame and standard may be bolted to the floor in any convenient manner.

On the rear end of the side-pieces a are 105 bearings $e-e$ for a shaft f upon which is mounted the core g of a paper supply roll h . Bearings $i-i$ are bolted to the upper edges of the side-pieces a and support the shaft 115 of a guide roller 16, and the shaft 17 of a guide 110 roller 18 above said roller 16 and out of contact therewith. The web h' of paper passes

from the roll h beneath the roller 16, upward in front thereof to the back side of the roller 18, and then over the top of said roller 18, forward, to the perforating and slitting mechanism. The rollers 16 and 18 assist in straightening the web h' in its forward travel from the paper supply roll.

The perforating mechanism comprises four rollers, namely, an upper perforator 19, a lower perforator or platen 20 and tension rollers 21 and 22, both of the latter being normally in contact with said platen, the roller 21 bearing against the lower rear quadrant thereof and the roller 22 against the lower front quadrant. The two perforators are by preference slightly separated. The perforator 19 is mounted on a shaft 23 journaled in bearings $j-j$ on the side pieces a forward of the positions occupied by the bearings i , but somewhat higher than the latter since the upper edges of the front portions of said side-pieces are raised considerably above the corresponding edges back of the same, as will be clearly seen in Fig. 1. This difference in height is made to enable the web h' to pass from the guide roller 18 to the tension roller 21 along a substantially horizontal plane, but is not an important feature. A gear 24 is fast on one end of the shaft 23 outside of the adjacent bearing. The platen 20 is mounted on a shaft 25 which is journaled in the side-pieces a , directly below the shaft 23. Both terminals of the shaft 25 project beyond the side-pieces. A gear 26, meshing with the gear 24, is fast on one end of the shaft 25, and the opposite terminal of said shaft carries a loose pulley 27 and two tight pulleys 28 and 29. The pulleys 27 and 28 are for the driving belt (not shown) of the machine.

On the inside face of the taller portion of each side-piece a are two angular lugs 30, from each of which a bolt or rod 31 having a head 31^a extends, and a box 32 is slidingly mounted on such rod. A spring 33 encircles said rod between its head and the box 32 thereon. There are four such boxes and the trunnions or shafts 34 of the tension rollers 21 and 22 are journaled therein in such a manner that they can be easily removed therefrom when said rollers are respectively forced rearward and forward, against the resiliency of the springs 33, a sufficient distance in each direction, the upper sides of the boxes being open. The springs 33 normally force the boxes towards each other and carry the tension rollers against the platen, and when the parts are thus disposed the open sides of said boxes are covered by the horizontal flanges 60 of the lugs 30 so that the shafts 34 cannot work out of their bearings. The bolts or rods 31 may be adjusted, if desired, to increase or decrease the amount of tension exerted by the springs 33.

The paper passes from the guide roller 18

to and beneath the tension roller 21 upward over the platen 20, downward beneath the tension roller 22 and forward and upward to the winding spindle 35 at the front or delivery end of the machine. This paper is an imperforate and uncut web until it reaches the top of the platen 20 where it is perforated, and directly thereafter it is slit, as will be presently explained.

The perforator 19 is a roller having a plurality of serrated knives 36 set axially therein in cross-section, with the teeth extending beyond the periphery thereof, and held in place by means of wedge-shaped bars 37 and screws 38, the knives and bars extending parallel with the axis of the roller. Upon loosening the screws 38, the knives 36 can be removed or readjusted. In the present instance there are three knives and the teeth of each are long enough, not only to bridge the space between the peripheries of the perforator 19 and platen 20 on a vertical line cutting their centers, but to enter a corresponding longitudinal slot 39 in said platen, as will be apparent from the explanation below. The platen 20 is also a roller having therein the same number of slots 39 as there are knives 36, and said platen and the perforator above are so arranged relative to each other, that, when revolved, each of said slots receives the teeth on the associated knife. A strip or buffer 40, of wood or other suitable material, is placed in each slot 39 on the side where the teeth of the knife leave said slot, and the arrangement is such that said teeth contact with said buffer before passing out of the slot. It will now be seen that the knives 36, operating in conjunction with the buffers 40, perforate the paper laterally without completely severing it, as indicated at h'' in Fig. 3, so that the paper can be easily torn apart in the usual manner for use. The complete operation is this: Each set of teeth presses the paper into the corresponding slot and against the buffer therein with sufficient force to cut through the paper, and then releases the latter and passes clear of it without tearing. The tension rollers 21 and 22 which are revolved with and by the platen, serve to hold the paper tightly in place on said platen while passing over the same to be perforated, and immediately afterward slit as will presently appear. One tension roller only might be used, or the position of one or both changed, but it is believed the best results are obtained by using two and arranging them substantially as shown. The platen together with the tension rollers serve as a feed for the paper and said platen also forms a part of the slitting mechanism in addition to being a part of the perforating mechanism.

In order to adapt the platen 20 for slitting as well as perforating purposes, a series of narrow annular grooves 20^a is formed therein, the grooves corresponding in number with

the slitters 41. The slitting mechanism which I will now describe in full, divides or slits the web h , after being perforated, into a plurality of strips h'' which enter into the formation of the small rolls h''' . Six rolls h''' of the finished product are shown in the first view. At the time the strips h'' are formed, if the web h is too wide, as in the present case, the surplus is trimmed off from the edges and wound into narrow rolls on the spindle 35 along-side of the rolls h''' , the narrow strips or trimmings and rolls being indicated by the characters k and k' , respectively. As a usual thing, however, the paper procured should be of the right width and there will then be no need of trimming at either edge. The slitters 41, which are arranged in a series, are provided with adjustable means of support. As many slitters are furnished as there are to be cuts in the paper—seven in the present instance; the two outside slitters, however, which serve as trimmers, would not be needed if the paper were of just the proper width for the required number of small rolls. Each slitter 41 is attached by a screw 42 to a slotted arm 43 slidably mounted in a lug 44 on a carrier 45 and held in place by a screw 46 passing through the slot into said lug.

Each carrier 45 is mounted on a shaft 47 which is in turn mounted in brackets l bolted against the inside faces of the taller portions of the side-pieces a , the carrier being split at 48 and clamped tightly around said shaft by means of a screw 49. Arms m extend forward from the members j over the shaft 47 to hold the latter in its bearings in the rear terminals of the brackets l ; upon removing or otherwise displacing said arms, said shaft, with the carriers, etc. mounted thereon can be taken out of the machine. Upon loosening the screws 49 the carriers with the slitters can be laterally adjusted on the shaft 47, and said slitters, which are arranged to enter the grooves 20^a in the platen, can be raised or lowered by reason of the adjustment afforded by the screws 46. It will now be seen that, when the paper is drawn between the grooved roller and the slitters, it will be cut longitudinally, and the construction and arrangement of parts is such as to cause the paper to be cut without tearing.

The buffers 40 are cut away adjacent to the grooves 20^a in the platen 20 so as to render such grooves continuous, as shown at 90 in Fig. 9, and at the intersections of the slots 39 with said grooves said slots are closed by continuations 91 of the periphery of said platen whereby the edge of each slot against which the corresponding slitter 41 bears is made practically without a break and a support for the paper is afforded at this point. The construction and arrangement just described enables the paper to be cut without tearing or wrinkling.

The winding spindle 35, which receives the paper after it passes the slitting mechanism, is revolved by a shaft 50 with which it is connected, one end of said shaft being journaled in a bearing n on the standard d and the other end in a bearing n' on the adjacent side-piece a . One end of the winding spindle 35 is supported by a bearing n'' on the front end of one of the side-pieces a , the bearing n' being on the end of the other side-piece. Since this spindle has to be frequently disconnected from its driving shaft I provide such shaft at one end with a pin 51 and recess and groove the connecting end of the associated spindle, as best shown at 52 in Fig. 5, to receive the end of the shaft with the pin. This arrangement affords a convenient means of connection and disconnection between the spindle and its shaft. The end of the spindle 35, opposite that which is adapted to be connected with the shaft 50, is provided with a pindle 53 upon which is a loose sleeve 54, shown in section in Fig. 7, to rest in the associated bearing n'' . Of course, the loose sleeve 54 may be omitted.

Inasmuch as there is great danger of tearing the paper after being cut into strips and while being wound onto the spindle, if a constant or unyielding force be applied thereto, I have provided a driving tension for the shaft 50, which comprises a disk 55, an integral sleeve 56 tight on the shaft, a pulley 57 loosely mounted on said sleeve, a friction member 58, of pasteboard or other suitable material, interposed between adjacent faces of the disk and pulley, an adjusting nut 59 and a spiral spring 60, the latter being interposed between the pulley and nut. The sleeve 56 is screw-threaded to accommodate the nut 59. A collar 61 tight on the shaft, at the outer end of the sleeve 56, prevents the nut 59 from coming off of said sleeve. These parts are all clearly shown in Fig. 4. This friction device operates as follows: The pulley 57 may revolve constantly, but when the resistance offered by the paper is greater for any reason than the frictional resistance afforded by the member 58 and contacting parts, the disk 55 ceases to rotate, thus bringing the shaft upon which it is mounted and the attached winding spindle to a stop. The amount of frictional resistance is regulated by screwing the adjusting nut 56 nearer or farther away from the pulley, accordingly compressing or relaxing the spring 60 and increasing or decreasing the amount of frictional contact between the pulley and the member 58 and the disk and said member. This is a valuable feature of my invention because it always enables me to employ a driving medium sufficiently strong to revolve the winding spindle yet weaker than the force necessary to break or tear the paper by tensile strain. If desired, the friction member 58 may be omitted and adjacent surfaces of

the disk 55 and pulley 57 brought into contact and depended upon for the necessary frictional resistance.

A belt 62 connects the pulley 29 on the shaft 25 with the pulley 57 on the shaft 50. It will now be seen that the power for the entire mechanism is furnished by and from the pulley 28 on the shaft 25.

The winding spindle which I prefer to use 10 consists of a roller, best shown in Figs. 6 and 7, having therein a longitudinal slot 63 opening through the periphery, and a spline 64 inserted in said slot in such a manner that it will bear against the cores upon which the 15 small rolls $\frac{1}{4}$ " are wound and prevent them from turning independently of the spindle, one such core being shown at 65 in Figs. 1 and 6. A screw 66 is set into the slot 63, adjacent the end which connects with the shaft 20 50, and one or more spiral springs 67 are let into recesses in the bottom of said slot between said screw and the opposite end of the spindle. One end of the spline 64 is beveled and bifurcated at 64° , and the opposite end 25 of said spline is provided with a strap 68 to serve as a handle in withdrawing the spline from the spindle and the rolls thereon. In practice, the spline 64 is placed in the slot 63 on the spring or springs 67, with the forked 30 end of said spline beneath the head of the screw 66, and said spring or springs thrust the spline outward against the inner surfaces of the cores 65, thereby holding them against independent movement. In the action of 35 the spline just described the screw 66 serves as a fulcrum. After the rolls have become of the proper size, the spindle is first removed from the machine and then from the rolls, the last operation being much more easily 40 and expeditiously performed than heretofore owing to the peculiar construction of the spindle, the spline yielding readily under pressure when grasped at the end opposite the bifurcation 64° , and so offering very little 45 resistance to the withdrawal of the spindle.

To prevent backlash of the paper supply roll $\frac{1}{4}$ and insure an even draw on the paper therefrom, a tension device, as shown in Figs. 3 and 10, may be used. This tension device 50 comprises a flanged disk 69 adapted to be secured to one end of the shaft $\frac{1}{4}$ by means of a set-screw 70, a yoke 71 made in two pieces pivoted together at 72, and a connecting bolt 73. A dog 74 extends from the yoke 71 to 55 contact with a stop pin $\frac{1}{4}$ projecting from the adjacent side-piece of the frame, such dog bearing on top of such pin. Now, as the shaft $\frac{1}{4}$ with the disk 69 revolves, the yoke 71 acts as a drag since the pin $\frac{1}{4}$ prevents said 60 yoke from rotating through the medium of the dog 74. The amount of frictional resistance offered by the yoke to the disk is regulated, of course, by the bolt 73. The device can be easily and quickly applied to and re- 65 moved from the shaft.

It is to be understood that the teeth are omitted from the perforating knives 36 adjacent the grooves 20^a in the platen, in order to leave corresponding portions of the paper imperforate until they reach the slitters 41, 70 otherwise the paper would be liable to tear.

The operation of the machine will be generally understood from the foregoing description, but an explanation of the manner in which the paper from the source of supply or 75 large roll is first started through the machine seems desirable. The web is first led under and over the rollers 16 and 18, next under the rear tension roller which is forced backward against its springs to enable this to be done, 80 over the platen, and under the front tension roller which is forced forward at the time, and thence finally to the winding spindle where it is fastened to the cores on said spindle, generally by pasting; then the shaft 47, 85 which had previously been removed by preference, is replaced in its bearings with the slitters in position. The machine is now started and run until the small rolls are of the required size, when the machine is stopped 90 and the spindle is disconnected and taken out of such rolls, the strips having been cut across by hand or otherwise before removing the spindle from the machine. Inasmuch as the small rolls are now held together by the 95 uncut paper which extended from the platen to the spindle at the start, they must be cut apart; or, if desired, this uncut paper may be severed and removed before commencing to wind the strips, in which event, as also when 100 subsequent small rolls are to be wound, it is simply necessary to bring the front ends of the strips onto the spindle or the cores thereon and there attach them by pasting or otherwise. The waste of paper is slight, in 105 case the uncut portions are thrown away, however, much less than when the slitters are farther back in the machine. At each revolution of the present perforator the webs are each divided into three sheets crosswise, and 110 these, in turn are slit lengthwise into six sheets by the slitters.

What I claim as my invention, and desire to secure by Letters Patent, is—

1. The combination, in a roll toilet paper machine, with means for holding the paper supply, combined perforating and slitting mechanism comprising a perforator and a slitter with a platen common to both, of a winding spindle, and a driving tension therefor having a predetermined amount of resistance and adapted to yield and permit said spindle to cease revolving when such resistance is overcome.

2. Combined perforating and slitting mechanism, for a roll toilet paper machine, comprising a rotary perforator provided with serrated knives, a slitter or slitters, and a rotary platen having longitudinal slots therein to receive the teeth on said knives and an annular 125

- groove or grooves therein to receive said slitter or slitters, the latter being suitably mounted in operative relation with said platen.
3. Perforating mechanism, for a roll toilet paper machine, comprising a rotary perforator provided with serrated knives having no movement independent of the perforator, and a rotary platen having annular grooves and longitudinal slots therein with buffers of yielding material in said slots adapted to receive the teeth on said knives, each of said buffers being placed against one side of its slot and cut away at the points of intersection with said grooves.
- 10 4. Perforating mechanism, for a roll toilet paper machine, comprising a rotary perforator provided with serrated knives, and a rotary platen having annular grooves and longitudinal slots therein with buffers in said slots, each of said buffers being cut away at the points of intersection with said grooves, and the periphery of said platen being continued across the slots at points adjacent to the intersections of the slots with the grooves.
- 20 5. Slitting mechanism, for a roll toilet paper machine, comprising a roller or platen having an annular groove therein, a loosely mounted shaft, a carrier adjustably mounted on said shaft, an adjustable arm slidably connected with the carrier and extending at substantially right-angles thereto, means for firmly holding said arm after adjustment, and a slitter mounted on the arm and adapted to enter the groove in said platen.
- 30 6. Combined perforating, feeding and slitting mechanism, for a roll toilet paper machine, comprising a rotary perforator provided with serrated knives having no movement independent of the perforator, a rotary platen having slots which receive the teeth on said knives and annular grooves therein, the perforator and platen being always out of contact, a series of slitters arranged and adapted to enter said grooves, and rollers tensioned against such platen to hold paper in contact therewith while being perforated and slit.
- 40 7. The combination, in a roll toilet paper machine, with a shaft having a pin in one end, of a winding spindle grooved and recessed at one end to receive the end of said shaft which is provided with the pin.
- 50 8. A driving tension, for a roll toilet paper machine, comprising a rotary shaft, a disk provided with a sleeve tight on said shaft, a pulley loose on said sleeve, and means mounted on the sleeve to cause said pulley to frictionally engage said disk.
- 60 9. A driving tension, for a roll toilet paper machine, comprising a rotary shaft, a disk provided with a sleeve tight on said shaft, a pulley loose on said sleeve, a nut threaded to the sleeve, and a spring between said pulley and said nut.
10. A driving tension, for a roll toilet paper machine, comprising a rotary shaft, a disk provided with a sleeve tight on said shaft, a pulley loose on said sleeve, a spring between said pulley and said nut, and a collar tight on the shaft at the end of the sleeve adjacent the nut.
- 15 11. A winding spindle, for a roll toilet paper machine, comprising a roller having a longitudinal slot therein and provided with a spline in said slot, a fulcrum member in the slot to retain one end of said spline in place, and resilient means to normally force the spline in part beyond the periphery of said roller.
- 20 12. The combination, in a winding spindle for a roll toilet paper machine, with a roller having a longitudinal slot therein and provided in such slot with resilient means and at one end with a fulcrum member, of a spline arranged and adapted to enter said slot and to engage said fulcrum member and bear against said resilient means, the end of such spline which engages the fulcrum member being thereby held against the action of the resilient means.
- 25 13. The combination, in a tension device for a roll toilet paper machine, with a paper supply roll shaft, and a support therefor, of a disk tight on said shaft, a two-part yoke carried by said disk and provided with a dog, means to tighten and loosen said yoke about the disk, and a stop pin extending from said support into the path of said dog.
- 30 14. The combination, in a roll toilet paper machine, of a suitable frame, means for holding the paper supply at the back of such frame, a winding spindle at the front of said frame, a rotary perforator provided with serrated knives having no movement independent of the perforator, a series of slitters, and a rotary platen having longitudinal slots therein to receive the teeth on said knives and annular grooves to receive the edges of said slitters, the perforator, slitters and platen being located between the holding means and the spindle with the slitters between the platen and spindle.
- 35 15. The combination, in a roll toilet paper machine, of a suitable frame, means for holding the paper supply at the back of such frame, a winding spindle at the front of said frame, a rotary perforator provided with serrated knives, a series of slitters, and a rotary platen having longitudinal slots therein to receive the teeth on said knives and annular grooves to receive the edges of said slitters, the perforator and platen being always out of contact and the perforator, slitters and platen being located between the holding means and the spindle with the slitters between the platen and spindle.
- 40 16. The combination, in a roll toilet paper

machine, of a suitable frame, means for holding the paper supply at the back of such frame, a winding spindle at the front of said frame, a rotary perforator provided with serrated knives having no movement independent of the perforator, a series of slitters, and a rotary platen having longitudinal slots therein to receive the teeth on said knives and annular grooves to receive the edges of said slitters, the perforator and platen being always out of contact and the perforator, slitters and platen being located between the holding means and the spindle with the slitters between the platen and spindle.

17. The combination, in a roll toilet paper machine, of a suitable frame, means for holding the paper supply at the back of such frame; a winding spindle at the front of said frame, a rotary perforator provided with serrated knives, a series of slitters, a rotary platen having longitudinal slots therein to receive the teeth on said knives and annular grooves to receive the edges of said slitters, the perforator and platen being always out of contact and the perforator, slitters and platen being located between the holding means and the spindle with the slitters between the platen and spindle, and rollers tensioned

against the platen to retain the paper in close contact with the latter.

18. The combination, in a roll toilet paper machine, of a suitable frame, means for holding the paper supply at the back of such frame, a winding spindle at the front of said frame, a rotary perforator provided with serrated knives having no movement independent of the perforator, a series of slitters, a rotary platen having longitudinal slots therein to receive the teeth on said knives and annular grooves to receive the edges of said slitters, the perforator and platen being always out of contact and the perforator, slitters and platen being located between the holding means and the spindle with the slitters between the platen and spindle, rollers tensioned against the platen to retain paper in close contact with the latter, and straightening or guide rollers, one above the other, between the holding means and the platen.

In testimony whereof I have signed my name to this specification in the presence of two subscribing witnesses.

GEORGE HENRY SIBLEY.
